UNITED STATES PATENT OFFICE.

WILLIAM C. ANDERSON, OF CINCINNATI, OHIO.

CIGAR MOUTH-PIECE.

SPECIFICATION forming part of Letters Patent No. 319,165, dated June 2, 1885.

Application filed May 2, 1884. (No model.)

To all whom it may concern:

Be it known that I, WILLIAM C. ANDERSON, of Cincinnati, in the county of Hamilton and State of Ohio, have invented a new and useful Improvement in Cigar Mouth-Pieces, which improvement is fully set forth in the following specification and accompanying drawings, in which—

This invention relates to cigar-tips; and the novelty consists in the tip being made flexible and elastic and having a tubular re-enforcing portion inserted in the contracted part, all as will be hereinafter fully explained.

As shown in the accompanying drawings, A represents a short section of the tube, upon which is placed an elastic flaring-tube, B. This tube B is preferably somewhat smaller in diameter than the end of a cigar and designedly of the same shape or configuration, so that when it is placed over the end of a cigar it will grasp and hold the cigar tightly, with the end of the cigar resting against the tube A.

As shown in Fig. 2, the tubular part A is made of some hard substance, so that the exterior tube, B, need not be hardened or vulcanized.

The tube B is made of elastic material best 30 adapted for the purpose, and should be of sufficient consistency to hold the cigar firmly.

It will be observed from the above description that I strongly re-enforce that part of the mouth-piece which is gripped between the 35 teeth, leaving the part in front of it sufficiently flexible to accommodate itself closely to the tapered tip of a cigar.

Having described my invention, what I claim as new is—

A flexible and elastic cigar-tip having a tubular re-enforcing portion inserted into the contracted portion thereof, substantially as described.

In testimony that I claim the foregoing I 45 have hereunto set my hand, this 28th day of April, 1874, in the presence of witnesses.

WILLIAM C. ANDERSON.
